RAZOR BLADE MAGAZINE

James M. Austin, Old Westbury, N. Y.

Application October 15, 1948, Serial No. 54,617

1 Claim. (Cl. 206—16)

1 This invention relates to razor blade magazines.

The general object of the invention is to provide an improved razor blade magazine which eliminates the need for handling the blade in loading a razor.

Another object of the invention is to provide a razor blade magazine incorporating also provision for removal and storage of used blades.

A further object of the invention is to provide a razor blade magazine adapted for use with double edged blades of the commonest type sold and with any of a variety of razors or holders with which such blades may be used.

For a full understanding of the invention, a detailed description of a razor blade magazine embodying the invention in a preferred form will now be given in connection with the accompanying drawing and the features forming the invention will be specifically pointed out in the appended claims.

In the drawing:

Figure 1 is a view in central vertical section of a magazine embodying the invention in a preferred form;

Figure 2 is a section on the line 2—2 of Figure 1;

Figure 3 is a plan view of the magazine of Figure 1;

Figure 4 is a view similar to the lowest part of Figure 1 and showing the parts in position for ejecting a blade;

Figure 5 is a view showing the method of using the device in removing a used blade;

Figure 6 is a view similar to Figure 1 and showing a modified form of magazine;

Figures 7 and 8 are horizontal and vertical sections, respectively, of a second modification; and

Figures 9 and 10 are horizontal and vertical sections, respectively, of still another modification.

Referring now to Figures 1—5, the magazine comprises end walls 1 and 2, and side walls 3 and 4, all of which may be formed integrally by molding from plastic or forming from sheet metal or in any other convenient way. A partition 5 divides the interior of the magazine into a new blade compartment below the partition, and a used blade compartment above it. The partition may be held in place in any convenient manner and in the type of construction shown is conveniently assembled by insertion from the top, past a number of upper nibs or projections 6 so that it springs or snaps into place between these projections and a number of corresponding lower projections 7. The partition 5 carries a central rib 8 adapted to fit the central aperture or cut

out of a double edged blade 9 as shown clearly in Figures 1, 2 and 4.

A stack of blades, ordinarily about twenty of them, will be supported by a lower shoulder 10 formed on the rib 8 and by a shoulder or ledge 11 formed on the bottom of the end wall 2 of the magazine. The lowermost blade is therefore supported by the shoulder 11 underlying one of its ends (indicated at 12 in Figure 2) and by the ledge 10 underlying the blade at one end of the central slot or cut out as indicated at 13. The stack of blades is pressed down against the supports 10 and 11 by means of a spring or springs 14 and with sufficient force to prevent accidental dislodging of the blade.

No attempt is made in the drawing to show the thickness of the blades accurately. They will ordinarily be about .006 in. thickness, so that a stack of twenty of them may only be about one-eighth of an inch in thickness.

The form of the central aperture in the blade is immaterial since the rib 8 requires only a few points of engagement along its sides and at its ends for accurately positioning the stack. The side walls 3 and 4 are spaced apart sufficiently to provide clearance between them and the edges of blades stacked on the rib 8, thus preventing any possibility of damage to the cutting edges.

A lower corner of the rib 8 is cut away as at 15 to permit sliding the lowermost blade of the stack (to the left in Figures 1 and 4) so that it passes off the supports 10 and 11 and may drop into a razor. A spring steel or similar L-shaped ejector member 16 is fastened to the end wall 2 as at 17 and its lower end 18 extends through a slot or opening in the wall 2 in alignment or registry with the lowermost blade of the stack. Pressing this spring inwardly with the thumb from the position of Figure 1 into that of Figure 4 will push the lowermost blade of the stack over sufficiently so that it is no longer supported by the ledges 10 and 11 and drops down and out of the magazine as indicated in Figure 4. As is apparent, if the magazine is held over a razor in open condition, a blade may be dropped thereon without handling with the fingers. It is immaterial whether the razor used has a central bar, a series of studs or corner engaging members for positioning the blade, and the magazine may be used on razors of any of these types. Also, where the blade positioning elements are on a cap which is separable from the razor handle, as in some old style razors, the blade may be dropped on the cap.

The upper end of the magazine is provided with spring catches 20 fastened thereto as by means of screws 21 and serving to retain a stack of used

blades within the upper compartment of the magazine. Moss or other elastic substance 22 may be utilized to hold a stack of used blades up against the spring catches 20 in the position shown in Figure 1. In removing a blade, the upper end of the magazine is pressed against the end of an open razor as indicated in Figure 5. The catches 20, being slanted as at 23, will spring apart so as to pass over the ends of the blade but, as soon as they have done so, will snap together as indicated in Figure 5 for holding the blade. The magazine may be pressed down on top of the razor, while held vertically or may be held horizontally or in any other convenient position which does not cause the blade to drop out prematurely.

The normal operation of the device involves: first, the opening of the razor so as to expose the blade therein, in whatever way is provided for the razor in question; secondly, the used blade end of the device is pressed down onto the used blade in the razor until the blade is caught by the catches 20, at which time the magazine is withdrawn, thus removing the used blade; thirdly, the magazine is reversed so as to bring the bottom blade of the stack of new blades in position over the blade retaining member or members of the razor and the ejector 16 is pressed to drop the blade into the razor; the razor is now closed in whatever way may be provided and the operation is completed.

Sufficient space will be provided in the used blade compartment to hold as many blades as are sold in the stack of new blades within the magazine. When all new blades have been used, the magazine may be discarded or returned and exchanged for a fresh magazine.

The central supporting rib 8 may be modified in various ways, to provide for freeing a blade by transverse movement thereof. In particular, the structure may be modified as indicated in Figure 6, in which corresponding parts are indicated by the same numerals as used in connection with Figures 1 to 5. The central rib 8a is generally the same as the rib 8 previously described and is formed with a lower shoulder 10a which is the same as the shoulder 10. Instead of cutting away the lower corner thereof as at 15, this corner is rounded off as indicated at 15a. As will be apparent, when the ejector 16 is operated, the lowermost blade will be pushed downwardly slightly as it comes against the rounded corner 15a and will then be snapped out of position. The radius of the rounded corner 15a is selected so as to prevent injection by friction or otherwise of the immediately overlying blade.

In Figures 7 and 8 a further modification is illustrated, in which the ledge 11 is eliminated and the blade is supported on ledges formed on a bar 8b which replaces the bar 8 of previous figures. This bar 8b is formed with lateral enlargements or ribs 30 and 31 adapted to fit within diamond shaped or similar cut outs in a blade. At their lower ends, the gibs 30 and 31 are formed with ledges 32 and 33 for supporting the blade as indicated in Figures 7 and 8. A lower corner of the bar 8b is rounded off as at 15b, much as in the embodiment of Figure 6, to permit transverse movement of the blade for ejection. As will be apparent, movement of ejector 16 pushes the lowermost blade transversely (to the left of Figure 8) so that the blade passes off the ledges 32 and 33 and is dropped into a razor. In Figure 7, for clearness, the blade outline is indicated in phantom, and a blade with a differently shaped central aperture from that shown in Figure 1 is selected for the purpose of illustration.

The ejector means may also be associated with the blade carrying rib and mechanism of this type is illustrated in Figures 9 and 10. In these figures, the rib 8c is generally similar to the rib 8b of Figure 8, and has similar blade guides or ribs 40 and 41, provided with blade supporting ledges 42 and 43. The rib 8c, however, is provided with a cut out 45 for accommodating an ejection spring 46 which is fastened to the cut out wall as at 47 and has a toe or blade ejecting member 48 at its bottom. The spring is preferably designed so that toe 48 presses downwardly against the lower edge 49 of the cut out 45 for maintaining it in a fixed vertical relationship to the blade supporting ledges 42 and 43. Toe 48 is positioned for engagement with a boundary of the blade cut out in the lowermost blade, upon leftward movement and may thus be employed for ejecting a blade in a manner otherwise similar to the operation of the ejector 16 of previous figures. The ejector spring 46 may be operated in a variety of ways. In the arrangement shown in the drawing, the spring is formed with a pair of projecting pins or ears 50 which pass through apertures in a generally U-shaped member 51, so that movement of member 51 will force the spring 46 transversely of the rib 8c for ejecting the lowermost blade. The opposite end 52 of the member 51 protrudes outwardly through the wall 2, through an opening 53 provided for this purpose. As will be apparent, pressing on the end 52 of member 51 will urge the spring 46 so as to bring the toe 48 thereof against the boundary of the blade central aperture for forcing the blade transversely of the rib 8c and ejecting it. A bifurcated spring 14c which straddles the rib 8c and ejector operating parts is provided for holding a stack of new blades down onto ledges 42 and 43.

What is claimed is:

A razor blade magazine comprising an open ended box, a central rib for slidably holding a stack of razor blades by means of central apertures therein, a supporting ledge formed on the lower end of the rib for extending under the bottom blade of the stack adjacent one end of the central aperture thereof, a supporting ledge on the box positioned to extend under the opposite end of the blade, spring means for pressing a stack of blades carried by the said rib downwardly onto the said supporting ledges and an ejector positioned for sliding the lowermost blade of the stack held on the rib longitudinally of the rib and off the ledges so that it may be dropped into a razor.

JAMES M. AUSTIN.
